UNITED STATES PATENT OFFICE.

JOHN M. MILLS AND KATE R. MILLS, OF TISKILWA, ILLINOIS.

GARMENT FASTENER.

Application filed April 10, 1926. Serial No. 101,124.

The invention relates to fasteners and more particularly to separable snap fasteners for garments and wearing apparel generally.

The invention provides a fastener which 5 securely holds the parts to be connected against casual disengagement in the event of slack, and which may be easily and quickly attached to an article or removed therefrom for repeated use, the fastener being 10 light, cheap and effective.

While the drawings illustrate a preferred embodiment of the invention, it is to be understood that in adapting the means to meet specific needs and requirements, the design 15 may be varied and such other changes in the minor details of construction may be resorted to within the scope of the invention as claimed, without departing from the spirit thereof.

For a full understanding of the invention and the merits thereof, reference is to be had 20 to the following description and the drawings hereto attached, in which,

Figure 1 is a detail view, illustrative of 25 a fastener embodying the invention,

Figure 2 is a detail view of the fastener having the complementary parts placed one 30 against the other to utilize the double snap, Figure 3 is an enlarged sectional view

on the line 3—3 of Figure 2,

Figure 4 is a view similar to Figure 2, showing the parts of the fastener arranged 35 to utilize the single snap action,

Figure 5 is an enlarged sectional view on 40 the line 5—5 of Figure 4, and

Figure 6 is a detail view of the pin for attaching a member to a garment or other 45 part to which the fastener is applied.

Corresponding and like parts are referred 50 to in the following description and designated in the several views of the drawings by like reference characters.

The fastener comprises complementary 55 parts, the one being a duplicate of the other and each being preferably constructed of sheet metal.

A detail description of one of the parts or members will suffice for a clear understanding of the invention. The fastener consists of a frame comprising a straight bar 1, a bow 2 connected at its extremities to the ends of the bar 1, a tongue 3 projected centrally from the bar 1 towards the middle of the bow 2 and hooks 4 at opposite ends 55 of the bar 1 and in line with a slot 5 formed in the bar 1 adjacent its inner edge. These

parts are of integral formation and constitute elements stamped from sheet metal. A stud 6 projects from the same side of the bar 1 as the elements 4 and in line with the 60 spring tongue 3. This stud is separate from the frame and riveted or otherwise attached thereto. A notch 7 is formed in the inner edge of the bow 2 opposite the extremity of the spring tongue 3 and is of a size to receive the stud 6 of a complementary part or member. The outer end of the stud 6 is made rounding so as to pass readily through the opening formed by the notch 7. Opposite sides of the stud 6 are notched, as indicated at 8 to receive the end of the spring tongue 3 and an edge portion of the bow 2 bordering upon the notch 7, whereby to positively hold the parts against casual disengagement, as shown most clearly in Figures 75 3 and 5.

A pin 9 is provided as means for securing the fastener to the fabric comprising a garment or other part and this pin has a flat head 10, preferably in the form of an eye. 80 The pin 9 is of a length so that its point and head will engage under opposite hooks 4 which constitute catches or guards. To attach the fastener a portion of the fabric is folded and passed through the slot 5 and 85 engaged by the pin 9 which is passed back and forth through the material, the parts being subsequently adjusted to admit of the ends of the pin lying beneath the catches or guards 4. The slot 5 is narrow and of a 90 width to prevent the withdrawal of the pin 9 therethrough after being engaged with the folded edge portion of the fabric. The slot terminates at its ends a short distance from the inner ends of the guards 4 and the space 95 between said guards and the adjacent side of the frame is such as to snugly receive the ends of the pin.

While the fastener may consist of a single member or part, nevertheless it is preferred 100 to employ two like members or parts which may be arranged, substantially as shown in Figures 2 and 3, or as illustrated in Figures 4 and 5. As shown in Figures 2 and 3, two like members or parts are placed one 105 against the other in reverse position, so that the stud of each passes through the opening of the other, thereby resulting in a double snap action. When two like parts or members are disposed substantially as shown 110 in Figures 4 and 5, the stud of one engages the opening of the other and the two mem-

bers face in the same direction and engage by a single snap action. The stud 6 is located exterior to the slot 5. Any element or part provided with a stud similar to the stud 6 may be engaged with the opening 7 of a single member or part.

The parts of the fastener are engaged by forcing the head of the stud 6 through the opening 7 and during this movement the end of the spring tongue 3 is pressed outwardly and when a notch 8 of the stud engages a portion of the bow 2 bordering upon the notch 7 the stud moves so as to enter the opening in a manner to receive the extremity of the tongue 3 and a portion of the bow opposite the tongue in the notches 8, as shown most clearly in Figures 3 and 5, thereby preventing casual disengagement of the parts. The engagement is thus effected by a snap action. To disengage the parts it is necessary to press the members away from one another so as to spring the extremities of the tongues from the studs engaged thereby. When the parts are arranged substantially as shown in Figures 2 and 3, the fastening is doubly secure, but ordinarily it

would be found sufficient to arrange the parts as indicated in Figures 4 and 5.

Having thus described the invention, we claim:

1. A fastener comprising a frame provided with a narrow fabric-receiving slot and having hooks at the ends of said slot and in line therewith to form guards to engage over the ends of a pin employed for holding the fastener to the fabric or like part.

2. A fastener comprising a frame including a bar and a bow, the latter having a notch in its inner edge to provide a stud receiving opening, said bar having a narrow fabric receiving slot and provided with hooks at the ends of the slot and in line therewith to engage over the ends of a pin, a spring tongue projecting from the bar and terminating adjacent the open side of the said notch and a stud projecting laterally from the bar in line with the spring tongue.

In testimony whereof we affix our signatures.

JOHN M. MILLS. [L.S.]
KATE R. MILLS. [L.S.]
